AUTOMATIC LOCK

John H. Hobson and Frank A. Burger,
Sulphur Springs, Ark.

Application February 23, 1942, Serial No. 432,076

1 Claim. (Cl. 292—45)

The device forming the subject matter of this application is adapted to be used on double doors, and the invention aims to provide a novel latch mechanism whereby one door will be held closed when the other door is moved to a closed position, the latch mechanism requiring no attention on the part of an operator.

It is within the province of the disclosure to improve generally and to enhance the utility of devices of that type to which the present invention appertains.

With the above and other objects in view, which will appear as the description proceeds, the invention resides in the combination and arrangement of parts and in the details of construction herein-after described and claimed, it being understood that changes in the precise embodiment of the invention herein disclosed, may be made within the scope of what is claimed, without departing from the spirit of the invention.

In the drawings:

Fig. 1 shows in perspective, a device constructed in accordance with the invention, one of the doors being opened;

Fig. 2 is a perspective wherein the doors are shown closed;

Fig. 3 is a section on the line 3—3 of Fig. 2;

Fig. 4 is a section on the line 4—4 of Fig. 1;

Fig. 5 is a section on the line 5—5 of Fig. 3;

Fig. 6 is a section on the line 6—6 of Fig. 2;

Fig. 7 is a perspective showing one of the latch bars, parts being broken away;

Fig. 8 is a perspective showing one of the supports for the latch bars.

The device forming the subject matter of this application is adapted to be used in connection with a supporting structure of any sort, such as a building having double doors.

A floor is shown at 1, a side wall appearing at 2, the numeral 3 marking a frame in the side wall, the frame defining a doorway 4.

The doorway 4 is controlled by a first door 5 and a second door 6, hinged to swing horizontally on the frame 3.

A recess 7 is formed in the floor 1 and is surrounded by a fixed keeper plate 8 having an opening 9.

At its free edge, the door 6 is provided with a lock 10 adapted to cooperate with a keeper 11 on the door 5, the door 6 carrying an upper wear plate 12 and a lower wear plate 14. The top portion of the frame 3 is provided midway between its ends with a striking plate 15.

The numeral 16 marks a lower support in the

form of a block, held on the door 5 by securing elements 17.

In its top and at one end, the lower support 16 has a transverse recess or superficial cavity, which is downwardly concaved, the recess defining opposed shoulders 18 and 19. At its recess end, the lower support 16 has a spindle 20.

A lower latch bar 21 is mounted to swing on the spindle 20 and is held thereon by any suitable means indicated at 22. The outer end of the latch bar 21 is rounded upwardly, as shown at 23, so as to have an easy engagement with the lower wear plate 14. The latch bar 21 is provided with a laterally extended finger 24, received in the recess 15 of the lower support 16 and adapted to cooperate with the shoulders 18 and 19, one at a time.

Near its upper edge, the door 5 is provided with a latch mechanism so nearly like that discussed that parts hereinbefore described are designated 20 by numerals already used, with the suffix "a".

The supports 16 and 16a are duplicates, a circumstance which cuts down cost of manufacture. The support 16a, however, is inverted from the position occupied by the support 16, the recess of the support 16a opening downwardly instead of upwardly. The end surface 23a of the latch bar 21a slopes downwardly instead of upwardly.

Another difference between the two latch mechanisms is that the latch bar 21 is a little longer than the latch bar 21a, and the spindle or pivot element 20 is so located in the latch bar 21 that the outer arm of the latch bar is longer than the inner arm: whereas, the spindle or pivot element 20a is so located in the latch bar 21a that the outer arm of the latch bar is shorter than the inner arm. The latch bars 21 and 21a, therefore, tend to overbalance into the positions shown in Fig. 1.

The result is that, when the parts are arranged 40 as shown in Fig. 1, the outer arm of the latch bar 21 is nearer the door 6 than is the outer arm of the latch bar 21a. As the door 6 is closed, the wear plate 14 comes into contact with the end surface 23 of the latch bar 21 first, and, later, the wear plate 12 comes into contact with the end surface 23a with the latch bar 21a. Less work is required to operate the latch bars 21 and 21a than would be the case if they had to be operated together.

The closing of the door 6 swings the inner arm 50 of the latch bar 21 down into engagement with the keeper plate 8, the inner arm of the latch bar 21a engages the striking plate 15, and the door 5 is held closed, without attention on the part of the operator. The lock 10 cooperates with the keeper 11, and both doors are held securely closed.

The latch bar 21 is held in the position of Fig. 1 by the engagement between the finger 24 and the shoulder 18, the latch bar 21a being held in the position there shown, by the engagement between the finger 24a and the shoulder 19a, because the support 16a is inverted with respect to the support 16.

After the door 5 has been opened, the latch bar 21a cannot swing accidentally to an inoperative position, in the direction of the arrow in Fig. 3, because the finger 24a engages the shoulder 18a, and the latch bar 21 cannot swing accidentally to an inoperative position, because the finger 24 engages the shoulder 19.

The engagement between the finger 24 and the shoulder 18 stops the latch bar 21 in a downwardly and inwardly slanting position, the engagement between the finger 24a and the shoulder 19a stopping the latch bar 21a in a downwardly and outwardly slanting position. The latch bars 21 and 21a, therefore, respond readily to the pressure exerted by the door 6, as it closes.

What is claimed is:

Latch mechanism for horizontally-swinging double doors, comprising upper and lower supports, each having a superficial, transverse cavity defining inner and outer rigid shoulders at the corresponding ends of the supports, upper and lower bar-latches, a pivot element connecting each latch with one support, the pivot elements

being so located that the inner arm of the upper latch is heavier than the outer arm thereof, and the outer arm of the lower latch heavier than the inner arm thereof, a rigid finger projecting laterally from each latch and located in the cavity, between the shoulders, the finger of the upper latch being so located as to engage the outer shoulder of the upper support and stop said latch in a downwardly and outwardly slanting position, the finger of the lower latch being so located as to engage the outer shoulder of the lower support and stop the lower latch in a downwardly and inwardly slanting position, the fingers being so located that they will engage the respective inner shoulders and stop the latches in substantially vertical positions, and means for mounting the supports on one of a pair of double doors, in such positions that the outer arms of both latches will extend across the free vertical edge of said door when the latches slant as aforesaid, the inner arm of the upper latch extending above said door, and the inner arm of the lower latch extending below said door, when the latches are in substantially vertical positions, the outer arm of the one latch extending outwardly farther than does the outer arm of the other latch, when the latches slant as aforesaid, to cause the latches to receive door-impact at different times.

JOHN H. HOBSON.
